DESIGN FOR A WINDOW SILENCER

Arthur P. Pfeil, Buffalo, N. Y.

Application March 8, 1935, Serial No. 55,790

Term of patent 7 years

To all whom it may concern:

Be it known that I, Arthur P. Pfeil, a citizen of the United States, residing at Buffalo, in the county of Erie and State of New York, have invented a new, original, and ornamental Design for a Window Silencer, of which the following is a specification, reference being had to the accompanying drawing, forming part thereof, in which

The dominant feature of my design resides in the bracket.

I claim:

The ornamental design for a window silencer, as shown and described.

ARTHUR P. PFEIL.
